J. TREGURTHA.
Paper-Ruling Machines.

Patented Oct. 13, 1874.

UNITED STATES PATENT OFFICE.

JAMES TREGURTHA, OF BOSTON, ASSIGNOR TO WILLIAM CHARLES DEMAIN,
OF CAMBRIDGE, MASSACHUSETTS.

IMPROVEMENT IN PAPER-RULING MACHINES.

Specification forming part of Letters Patent No. 155,815, dated October 13, 1874; application filed September 3, 1874.

To all whom it may concern:

Be it known that I, JAMES TREGURTHA, of Boston, in the county of Suffolk and State of Massachusetts, have invented certain new and useful Improvements in Paper-Ruling Machines, of which the following, taken in connection with the accompanying drawings, is a specification:

My invention relates to that part of the mechanism of a paper-ruling machine which controls the action of the pens, and usually called the "striker;" and it consists, first, in the use of a wheel mounted upon an axis parallel to the axis of the string or driving cylinder, and arranged to be driven by exterior contact with the periphery of said cylinder, and provided with adjustable cam-blocks fitted to and secured in grooves formed in the interior periphery of the rim of said wheel as a means of controlling the action of the pens.

My invention further consists in the combination, with a cam-wheel constructed, arranged, and operated as above set forth, of a stop or lug secured thereto, a pawl-lever arranged to be interposed in the path of said lug, and a latch-lever to lock said pawl-lever in position, and suitable devices for tripping said latch-lever to release said wheel, and allow it to revolve at the proper time.

My invention further consists in the use, in combination with a wheel provided with adjustable cam-segments, of a cam-lever made in two parts, and secured together by means of an axial clamping-pin, so as to form a rigid lever, one portion of which may, by loosening said axial pin, be swung to one side in a plane at right angles to the plane of movements of said lever, when acted upon by the cam, to facilitate the removal of the cam-wheel, and the substitution of another of different size, which becomes necessary as often as the size of the paper to be ruled is changed.

This lever is provided with a set-screw at the end which is farthest removed from the cam, which rests upon a lever or arm attached to and projecting from the pen-beam, and is the medium through which or by which

the pen-beam is vibrated to lift the pens from the paper at the proper time.

My invention further consists in attaching the pen-beam lever to said beam in such a manner that it may be adjusted about the axis thereof for the purpose of adjusting the lift of the pens; and it further consists in constructing said lever with a broad pad or table-like surface at its outer end, to receive the end of the set-screw in the end of the cam-lever, so as to allow of any desired amount of adjustment of the end of the pen-beam without breaking the connection between the two levers.

My invention further consists in the application of a similar pad or table to the outer or movable end of the lever, which operates the rocker-shaft, through which the latch-lever is depressed to release the stop-pawl, and allow the cam-wheel to revolve. Upon this pad rests the end of a set-screw attached to the movable end of a lever, firmly secured to a rocker-shaft above the pen-beam, from the opposite side of which projects another lever or arm, to the movable end of which is secured, upon a suitable axial pin, the ordinary trip-wheel for releasing the cam-wheel.

My invention further consists in giving to the trip-wheel more lift than is required to release the cam-wheel, and varying the time of such release by interposing between the trip-wheel and the latch-lever that locks the cam-wheel an adjustable point of contact in the shape of the set-screw last referred to.

My invention further consists in fitting said screw in a nut pivoted to the end of the rocker-shaft arm, so as to swivel therein, the axis of said nut being at right angles to the axis of the screw, in combination with a fixed guide, through which the lower end of said screw passes, said screw being raised or lowered to vary the time of the pens striking the paper.

In the drawings, Figure 1 is a plan of so much of a paper-ruling machine as is necessary to illustrate my improvements. Fig. 2 is a vertical transverse section on line *x x* on Figs. 1 and 3. Fig. 3 is a side elevation of the same. Fig. 4 is a detail, partly in section, il-

lustrating the construction of the cam-lever and its relation to the pen-beam lever, as well as the manner of securing the latter to the pen-beam. Fig. 5 is a section on line yy on Fig. 4. Fig. 6 is an elevation of the devices for stopping the motion of the cam-wheel, as seen looking in a direction opposite to Fig. 3; and Fig. 7 is a plan of a portion of the train of mechanism for operating the latch-lever to release the cam-wheel.

A A is the frame of the machine; B, the cloth or apron cylinder; C, the pen-bearing cylinder; and D, the apron-roll, mounted in bearings, made adjustable by means of the screw-nuts $a a$, all constructed and arranged in a well-known manner. E is the paper-carrying cloth or endless apron. F is the string-cylinder, mounted upon the driving-shaft F'. G and G' are the string-guide rolls, around which and the cylinder F are led the endless-string belts $b b$, in the usual manner. H is a disk-wheel, mounted upon a stud, c, set in the movable end of the radius-arm I, arranged to vibrate about its fulcrum-pin, to adapt its position to the size of the cam-wheel being used. The wheel H must have an exterior circumference about equal to the length of the piece of paper to be ruled, and is provided with a heavy projecting rim, H', upon one side, in the inner face of which are formed two grooves, d and d' , of unequal depths, in which may be inserted one or more segmental pieces of metal, e e, so formed as to project beyond the inner periphery of the rim H' a distance equal to the movement that it is desirable to impart to the cam-truck for lifting the pens from the paper. These segments are held in position by the set-screws f and f' , the screw f bearing against the segment in the groove d , and f' against the segment in the groove d' , said screw passing through solid metal below the bottom of the groove d and the segment contained therein, as seen in Fig. 2. The wheel H rests upon the periphery of the string-cylinder F, and is forced against it by the spring J or a weight with sufficient force to cause it to be revolved thereby when not prevented by the stop. K K' is a cam-lever, made in two parts, connected together by the axial clamping-bolt g, so as to form a rigid lever, and mounted upon the fulcrum-pin h, set in the stand L in a horizontal position, parallel to the axes of the wheel H and the string-cylinder F, and at right angles to the axial pin g, which secures the two parts K and K' of said lever together. The movable end of the part K of said lever is provided with a stud, i, set rigidly therein, and projecting therefrom parallel to the fulcrum-pin h, and upon which is mounted the cam-truck j, arranged to rest upon the inner periphery of the rim H' of the wheel H, or the segments e e set therein, said truck being located between the axis of the wheel and the point of contact of said wheel with the periphery of the string-cylinder. The opposite movable end of the lever K K' is provided with

the adjusting-screw k, the lower end of which rests upon the broad pad-like surface of the movable end of the lever l, secured to the end of the pen-beam M. The lever l is mounted loosely upon the threaded journal-shaft m, and may be adjusted about said journal and secured in any desired position by the screw n and nut o, fitted to and moving in the slot p formed in the plate q, secured permanently to the end of the pen-beam M, as seen in Fig. 4. The pen-beam M is made in two parts, secured together by the screws rr, and has permanently attached to one end thereof the smooth journal-shaft s, and to the other end the plate q, in which is journaled so as to revolve therein the threaded journal-shaft m, said shaft being so fitted to the plate q that, while it may revolve therein, it cannot be moved endwise therein. N and N' are two stands, in which the pen-beam M is mounted by means of the journal-shafts m and s, the stand N' being provided with a female screw-thread to fit the thread on the journal m, so that, by revolving the journal-shaft m, by means of the milled head t attached to its outer end, the pen-beam M may be moved endwise to adjust the pens laterally upon the paper being ruled. The stand N is secured to the top of the frame A by the screw u, and the stand N' is secured to the plate O by means of the thumb-nut P and a headed bolt passing through a slot in said plate, with the head below the plate, in a well-known manner, so that said stand may be adjusted in the direction of the length of the machine, for the purpose of squaring the pens to the work. Q is a rocker-shaft, mounted in bearings in the upper part of the stands N and N', directly over the pen-beam M; and R and R' are levers firmly secured thereto, and projecting from opposite sides thereof, as shown. The lever R is provided with a stud, v, upon which is mounted the trip-wheel S, having a portion of one side cut away, so as to fit or nearly fit the curve of the pen-bearing cylinder, upon which it rests, with the endless apron E interposed between, and provided with the small projecting tooth v', against which the sheet of paper strikes as it is carried forward by the endless apron E and string-bands b b, and by the continued forward motion of the paper said wheel is revolved, which raises the lever R, rocks the shaft Q, and depresses the outer end of the lever R'.

The lever R' has pivoted to the side of its outer end the nut w', through which passes the screw w, and in which it may be adjusted to vary the distance between its lower end and the lever a², rigidly secured to the rocker-shaft b², upon which it strikes when the lever R is depressed.

This adjustment is of great advantage, as admitting of a much finer adjustment of the time of the pens striking the paper at the head-lines.

The lower end of the screw w passes through

the guide c^2 , projecting from the stand N , and the swiveling attachment of the nut w' allows a free movement of the lever R' through the arc of a circle without causing the screw w to bind in its nut. The movable end of the lever a^2 is expanded into the form of a broad pad, upon which the end of the screw w will strike when it descends, into whatever position the pen-beam may be adjusted; and said lever is held up, when the pressure is removed, by the spring n^2 . *not shown*

The rocker-shaft b^2 is mounted in bearings in the stands c^1 c^1 , secured to the plate O , and has secured to its end, opposite the lever a^2 , another lever, d^2 , projecting therefrom, upon the same side as a^2 , the movable end of which rests upon one end of the latch-lever e^2 , provided with the shoulder e^3 , and pivoted at e^4 to the stand f^2 , as seen in Fig. 6.

g^2 is a stop-pawl, pivoted to the stand h^2 , the long arm of which depends from its fulcrum-pin, and rests upon the latch-lever e^2 , just forward of the shoulder e^3 , while its short arm is maintained in a position to be struck by the dog or lug i^2 , secured to the face of the rim H' of the wheel H , as seen in Figs. 3 and 6.

The lever e^2 is provided with a counterpoise-arm, c^5 , which causes the latch to operate by the force of gravity, and the same force causes the stop-pawl g^2 to assume a position to be latched after it has been tripped.

T T are gear-wheels, by which motion is imparted from the driving cylinder to the cloth or apron cylinder; and U is a crank, by which the machine is operated.

A great advantage is gained by the use of my improved cam-wheel, arranged as set forth, from the fact that any desired diameter of cam-wheel may be used without change in, or adjustment of, other parts of the mechanism, the cam-truck j on the end of the lever K always bearing the same relation to the point of contact of the wheel H with the string-cylinder; and, if the rim H' of all the cam-wheels is made of the same radial width, it follows that a wheel of any desired diameter may be substituted for the one in use without change in other parts of the mechanism, except to swing the radius-arm I into the proper position to bring the lower edge of the cam-wheel into contact with the periphery of the string-cylinder F , as described.

The peculiar construction of the lever K K' is for the purpose of facilitating the changing of the cam-wheels, which is done by loosening the axial bolt g and swinging the arm K with the truck j away from the cam-wheel H , when the cam-wheel, together with its supporting-arm I , may be raised, if necessary, and the wheel H be withdrawn from its stud, and another wheel of different diameter put in its place, when the arm K is again swung into position parallel to the face of the cam-wheel, with the truck j above the rim H' , and the axial clamping-bolt is screwed down

hard, when the machine is again ready for operation.

V is an arm projecting from the pen-beam, and carrying the adjustable gage-screw V' to regulate the fall of the pen in a well-known manner.

W is one of the ruling-pens, of usual construction, secured between the two parts of the pen-beam, also in a well-known manner.

What I claim as new, and desire to secure by Letters Patent of the United States, is as follows:

1. The wheel H , provided with the annular rim H' , projecting from its side, and one or more segmental cam-blocks e e , fitted to, and adjustable in, grooves formed in the interior face of said rim, substantially as described.

2. The combination of the cam-wheel H , radius-arm I , stud c , and string-cylinder F , all constructed and arranged to operate substantially as described.

3. The combination of the wheel H , provided with one or more segmental cam-blocks e e , projecting, from and adjustable in, grooves formed in the interior face of the rim H' , the stop-pawl g^2 , latch-lever e^2 , provided with the shoulder e^3 , the lug or dog i^2 , secured to the wheel H , all constructed and arranged with relation to each other, substantially as described, for the purpose specified.

4. In combination with the cam-wheel H , constructed, arranged, and operating substantially as set forth, the dog i^2 , the stop-pawl g^2 , the latch-lever e^2 , levers d^2 and a^2 , rocker-shafts b^2 and Q , levers R and R' , and the trip-wheel S , all arranged as described, for the purpose specified.

5. The combination of the lever R' , secured to and projecting from the rocker-shaft Q , the pivoted nut w' , screw w , and guide-bearing c^2 , all constructed and arranged substantially as described.

6. The lever K K' , made in two parts, clamped together by means of the axial clamping-bolt g , at right angles to its fulcrum-pin h , in combination with the wheel H , constructed, arranged, and operated substantially as described.

7. The lever l , attached to the pen-beam, and arranged to be adjusted about its axis, as set forth, in combination with the plate q , provided with the slot p , and the binding-nut o and screw n , substantially as described.

8. In combination with the pen-beam M , arranged to be adjusted longitudinally and transversely of the machine, to adjust the pens to the work, and the cam-lever K K' , arranged to impart a rocking motion to said pen-beam, the lever l , provided with a broad pad-like surface at its outer or movable end, substantially as described, for the purpose specified.

9. In combination with the rocker shaft Q , arranged to be adjusted longitudinally of the

machine in conjunction with the pen-beam M, and provided with the levers R and R' and trip-wheel S, the lever a^2 , made broad at its movable end, substantially as described, for the purpose specified.

10. The lever R', provided with an adjustable contact-point, in combination with the levers a^2 and R, and the trip-wheel S, arranged to depress the end of the lever R' a

greater distance than is required to release the cam-wheel, substantially as described.

Executed at Boston, Massachusetts, this 31st day of August, 1874.

JAMES TREGURTHA.
